FLYER

Elvin B. Robinson, Gastonia, N. C., assignor to Ideal Industries, Inc., Bessemer City, N. C., a corporation of North Carolina

Application April 7, 1955, Serial No. 499,863

12 Claims. (Cl. 57—117)

This invention relates to flyers for roving frames, slubbers and the like and, more especially, to a new type of flyer which is much less expensive than the old type which had to be cast or forged and machined.

It is an object of this invention to provide a flyer and method of making same in which the inverted U-shaped body which carries the yarn depositing mechanism or presser is made of a piece of metal tubing with the pilot member thereof, for affixing the same to the spindle, being made of another piece of metal suitably secured to the flyer, as by a pressed fit.

It is another object of this invention to provide a flyer having the inverted U-shaped member or body made of a piece of tubing with the leg of the body accommodating the depositing mechanism or presser being of smaller diameter or tapered so that, when the depositing mechanism is added thereto, the flyer will be in perfectly balanced condition.

It is another object of this invention to provide a flyer made of a piece of tubing with the presser attached thereto and in perfectly balanced condition with the central portion of the flyer being made of a separate piece securely mounted on the tubing.

Some of the objects of the invention having been stated, other objects will appear as the description proceeds when taken in connection with the accompanying drawings, in which—

Figure 1 is a side elevation of the improved flyer in association with parts of a roving frame shown somewhat schematically;

Figure 2 is an enlarged vertical sectional view through a portion of Figure 1;

Figure 3 is a top plan view of the flyer with the presser thereon;

Figure 4 is an enlarged vertical sectional view taken substantially along the line 4—4 in Figure 2;

Figure 5 is a fragmentary sectional plan view taken along the line 5—5 in Figure 7;

Figure 6 is a sectional plan view taken along the line 6—6 in Figure 2;

Figure 7 is an enlarged fragmentary elevation of the upper central portion of the flyer shown in Figure 1, and looking along line 7—7 in Figure 4, but omitting the spindle.

In the drawings the numerals 10 and 11 indicate the front rolls of a roving frame or slubber while 12 and 13 indicate the middle rolls. A roving frame has other rolls, all which is common to the art. The improved flyer is adapted to be used instead of the conventional flyer and is used on apparatus such as shown in U. S. Patent No. 2,046,376 of July 7, 1936, issued to P. A. Gwaltney et al.

The rolls 10—13 are mounted in suitable roll stands 15 and a strand of roving or sliver S passes through the rolls and is attenuated and moves into the improved flyer, the body of which is broadly designated at 16. The flyer works on a spindle 17 which is driven by any

2

suitable means, such as shown in said patent, in a right to left direction and the flyer rests on top of the spindle 17 while the spool or bobbin 18 is driven by a suitable whorl 19 in the same direction as, but at a lesser rate of speed than the flyer.

The flyer body 16 is an inverted U-shaped tubular member, preferably made from stainless steel, with the central portion or pilot member 20 thereof made of a separate piece but welded or otherwise secured to the tubular member 16. The pilot member 20 is affixed, as by a pressed fit, to the U-shaped member 16 or by any other suitable means such as being slid over one of the legs of the flyer and affixed in central position. The flyer body 16 has legs 22 and 23, part of the leg 22 being of lesser diameter than the leg 23 or being tapered so as to give the leg 22 lighter weight to compensate for a presser assembly 24 loosely mounted thereon.

The tubular pilot member 20 has a slightly tapered bore 25 therein for receiving the slightly tapered upper end portion of spindle 17. The tubular pilot member 20 has a transverse pin 47 therethrough which is adapted to fit into a notch 48 in the upper end of the spindle 17. The presser assembly 24 is similar in all respects to that shown more clearly in said patent.

The leg 22 has a slot 26 running its entire length and up to the point where the member 20 is affixed thereto. The slot 26 runs to the extreme free end of the leg 22 and is in open position before the bobbin is started but when the bobbin is filled partially or fully the lower end 30 of the presser assembly closes the slot 26.

The pilot portion 20 has a square broached hole 30 which extends downwardly and communicates with the enlarged tapered bore 25 in the lower portion of member 20. After the flyer 16 is fixed in position, this closes the lower end of hole 30 and the tubular body 16 has an opening or aperture 31 therein which communicates with the upper portion of the square hole 30. The flyer body 16 also has an opening 33 in its side which communicates with an enlarged tapered bore 34 in the pilot member 20 and the strand S passes downwardly through the bores 30, 31 and longitudinally through the leg 22 of the body 16. The roving S passes out of the bottom of leg 22 and is wound several times around the presser foot indicated at 35, and is then deposited onto the bobbin or tube 18.

In order to thread the strand into the flyer, the strand is inserted downwardly through holes 30, 31, 33 and 34. The operator then pulls the strand through hole 34 and inserts it in the leg 22 through slot 26. Thereafter, it is wound around the presser foot 35 and made fast to the bobbin 18.

It will also be noted that the leg 22 has a plurality of bores 36 therein to prevent suction from having any effect on same. The leg 22 is recessed and has a fitting 40 mounted in the same which accommodates one end 41 of the presser assembly 24 and the presser assembly has a vertical body portion indicated at 43 whose lower end has a rounded member 45 thereon to which one end of the presser foot 35 is connected. The rounded member 45 is cut away to permit threading of the strand S into the slot 26, preferably, when the bobbin 18 is empty.

Heretofore, flyers have been cast or forged of a single piece, with the exception of the presser assembly, and the subsequent forming and finishing operations required to balance the conventional flyer have been such that the flyer has been expensive to produce as compared to the present flyer. Also, the useful life of the conventional type of flyer has been limited due to ballooning of the legs thereof by centrifugal force. This is overcome in the new flyer due to the great strength of a tubular body as compared to a solid forged body.

Another outstanding feature of the improved flyer disclosed herein resides in the fact that the tubular body 16 is of the same internal diameter throughout its length thereby permitting polishing of the interior wall of the body 16 throughout its length with a polishing tool of corresponding size. Conventional flyers are provided with a funnel-like leg through which the roving passes in its course to the presser foot and the shape of this funnel-like leg has made it practically impossible to smoothly polish its interior surfaces.

It is seen that I have provided a flyer made of two separate pieces and suitably secured together so that the expensive method of making a flyer such as shown in said patent is eliminated and a perfectly balanced flyer is made out of two pieces of separate material fixed together. The roving S may also be threaded into the lower end of a slot 26, through the leg 22 and then through the bore 34 and through opening 33 and through the central portion of member 16 and up through the broached bore 30 and between the rolls of the roving frame.

In the drawings and specification there has been set forth a preferred embodiment of the invention, and although specific terms have been employed they are used in a generic and descriptive sense only and not for purposes of limitation, the scope of the invention being defined in the claims.

I claim:

1. An improved flyer for roving frames and the like comprising a tubular body having opposite ends bent to extend in parallel relationship and in perpendicular relationship to the central portion of the tubular body to form first and second legs thereon, a pilot member fixed on the central portion of the tubular body, said tubular body having an opening in the side of the central portion opposite from said legs, said pilot member having an axially extending hole therein coinciding with the opening in the central portion of the tubular body, said first leg being tapered for at least a substantial part of its length and being of lesser diameter at its free end than the diameter of the remaining portion of the tubular body, said first leg also being provided with a slot extending throughout its length for threading a strand of roving into said leg and through the opening in the body and the first-named hole in the pilot member, and a presser assembly loosely mounted on the first leg of the tubular body and having a presser foot thereon for feeding the strand of roving from the free end of the first leg of the tubular body to a bobbin.

2. A structure according to claim 1 wherein said first leg of the tubular body is provided with a plurality of longitudinally spaced holes therein to assist in balancing the first leg and the presser assembly with respect to the second leg of the tubular body.

3. A structure according to claim 1 wherein the hole in the pilot member, which communicates with the opening in the tubular body, is in substantially the shape of a quadrangle.

4. A structure according to claim 1 wherein the inner surface of the medial portion of said first leg is provided with a recess therein, a fitting mounted in the recess and projecting inwardly from said first leg and being provided with a groove therein for accommodating the corresponding end of the presser assembly.

5. An improved flyer for roving frames and the like comprising a tubular body being of uniform internal diameter throughout its length and having opposite ends bent to extend in parallel relationship and in perpendicular relationship to the central portion of the tubular body to form first and second legs thereon, a pilot member fixed on the central portion of the tubular body, said tubular body having an opening in the side of its central portion opposite from said legs, said pilot member having an axially extending first hole therein coinciding with the opening in the central portion of the

tubular body, said tubular body and said pilot member also having intercommunicating second holes therein disposed in substantially right-angular relation to the axis of the first hole in the pilot member, said first leg being 5 tapered for at least a substantially part of its length and being of lesser diameter at its free end than the diameter of the remaining portion of the tubular body, said first leg also being provided with a slot extending throughout its length and communicating with the second coinciding holes in the tubular body and the pilot member for threading a strand of roving into said leg and through the first hole in the pilot member and the opening in the central portion of the tubular body, and a presser assembly loosely mounted on the first leg of the tubular body and having a presser foot thereon for feeding the strand of roving from the free end of the first leg of the tubular body to a bobbin.

6. A structure according to claim 5 wherein said first leg of the tubular body is provided with a plurality of 20 longitudinally spaced holes therein to assist in balancing the corresponding leg and the presser assembly with respect to the second leg of the tubular body.

7. A structure according to claim 5 wherein the first hole in the pilot member, which communicates with the 25 opening in the tubular body, is in substantially the shape of a quadrangle.

8. A structure according to claim 9 wherein the inner 30 surface of the medial portion of the first leg is provided with a recess therein, a fitting mounted in the recess and projecting inwardly from one said first leg and being provided with a groove therein for accommodating the corresponding end of the presser assembly.

9. An improved flyer for roving frames and the like 35 comprising a tubular body having opposite ends bent to extend in substantially parallel relationship and in substantially perpendicular relationship to the central portion of the tubular body to form first and second legs thereon, a pilot member fixed on said central portion, said tubular body having an opening in the side of the central portion opposite from said legs, said pilot member having an axially extending hole therein coinciding with the opening in the central portion of the tubular body, said first leg being tapered for at least a substantial part of its length and being of lesser diameter at its free end than the diameter of the remaining portion of the tubular body whereby a strand of roving may be threaded through the hole in the pilot member and through said first leg, and a presser assembly loosely mounted on the first leg of the tubular body and having a presser foot 45 thereon for feeding the strand of roving from the free end of the first leg of the tubular body to a bobbin.

10. A structure according to claim 9 wherein the hole 50 in the pilot member which communicates with the opening in the tubular body is in substantially the shape of a quadrangle.

11. A structure according to claim 9 wherein the inner 55 surface of a medial portion of said first leg is provided with a recess therein, and a fitting mounted in the recess and projecting inwardly from said first leg and being provided with a groove therein for accommodating the corresponding end of the presser assembly.

12. In a roving frame or the like having a plurality 60 of upright spindles thereon and means for loosely supporting bobbins on said spindles so the spindles project upwardly above the bobbins, an improved flyer comprising an elongated tubular body having opposite ends bent to extend in substantially parallel relationship and in substantially perpendicular relationship to the central portion of the tubular body to form first and second legs 65 thereon, a pilot member adapted to fit upon a corresponding spindle and being fixed on the medial portion of the tubular body, said tubular body having an opening in the side of its central portion opposite from said legs, said pilot member having an axially extending hole 70 in its end opposite from the corresponding spindle and

75

coinciding with the opening in the central portion of the tubular body, said first leg being tapered for at least a substantial part of its length and being of lesser diameter at its free end than the diameter of the remaining portion of the tubular body, whereby a strand of roving may be threaded through the hole in the pilot member, the opening in the body and the first leg of the tubular body, and a presser assembly loosely mounted on said first leg and having a presser foot thereon for feeding the strand of roving from the free end of said first leg to a bobbin.
